Bertha A. Schedler, Inventor
By her Attorney
Maurice Block

UNITED STATES PATENT OFFICE.

BERTHA A. SCHEDLER, OF BRONXVILLE, NEW YORK.

DESIGN FOR A PARASOL.

52,545.

Specification for Design.

Patented Oct. 8, 1918.

Application filed July 2, 1918. Serial No. 243,076. Term of patent 7 years.

To all whom it may concern:

Be it known that I, BERTHA A. SCHEDLER, a citizen of the United States of America, residing at Bronxville, Westchester county, and State of New York, have invented a new, original, and ornamental Design for a Parasol, of which the following is a specification, reference being had to the accompanying drawing, forming part hereof, which represents a perspective view of a parasol, embodying my new design.

I claim:

The ornamental design for a parasol, as shown.

Signed at New York city, New York, this 29th day of June, 1918.

BERTHA A. SCHEDLER.

Witnesses:

Rose PERLMUTTER,
MAURICE BLOCK.
